UNITED STATES PATENT OFFICE.

CHARLES M. FITCH, OF KANKAKEE, ILLINOIS, ASSIGNOR TO SEARS, ROEBUCK AND CO., OF CHICAGO, ILLINOIS, A CORPORATION OF NEW YORK.

BURNER-REGULATING DEVICE.

Application filed November 2, 1925. Serial No. 66,136.

The invention has general reference to oil stoves or heaters of the wickless burner type in which the height of the flame is regulated by varying the level of the oil in the annular burner bowl. Usually the oil level is varied by raising or lowering the oil receptacle or burner bowl with reference to a constant level source, the bowl being connected with such source by means permitting of its up and down movements.

The object of the invention generally stated is to provide an improved adjusting or regulating means whereby the oil receptacle which is mounted for up and down movements may be readily and conveniently operated to vary the position of the receptacle, and which is adapted to sustain the receptacle in its adjusted position against accidental movement.

Briefly stated, I accomplish this result by means of an operating screw having a screw-threaded connection with a stationary part on the stove or heater structure and having an operating handle located forwardly in said structure and having an operative connection between the rear end of the screw and the receptacle to be raised and lowered.

In the accompanying drawings, I have illustrated one embodiment only of the invention, it being contemplated that various changes may be made by those skilled in the art without departing from the spirit and scope of the invention as expressed in the appended claims.

Figure 1 of the drawings is a fragmentary front elevational view of an oil stove having my improved adjusting means applied to a burner to raise and lower the same.

Fig. 2 is a vertical sectional view taken approximately in the plane of line 2—2 of Fig. 1.

Fig. 3 is a similar view taken approximately in the plane of line 3—3 of Fig. 1.

Fig. 4 is a rear view of the parts shown in Fig. 1.

In the embodiment selected for illustration, 7 designates an annular burner bowl of any ordinary or preferred construction communicating by means of a telescoping pipe connection 8 with a horizontally disposed oil supply pipe 9 leading to a convenient source of oil supply (not shown). 10 designates a horizontally disposed front plate extending lengthwise along the front of the stove and rigidly secured to the stove

structure in any suitable way (not shown). The front plate 10 comprises a vertical portion 11 and an upper rearwardly extending horizontal portion 12, the front or vertical portion being spaced a substantial distance 60 forwardly of the horizontal supply pipe 9.

Rigidly secured to the front plate 10 and extending rearwardly therefrom beneath and beyond the upper portion 12 of this plate is a supporting bracket 13 in the form 65 of a plate of substantial width having upper and lower flanges 14 and 15 and a front flange 16. The upper flange 14 and the front flange 16 are respectively secured to the horizontal and vertical portions 11 and 70 12 of the front plate 10. Near their rear ends said upper and lower flanges 14 and 15 are extended laterally somewhat to provide ears 17 and 18 which are apertured to receive the lower section 19 of the telescoping pipe connection 8. At its lower end said pipe section 19 may be secured to the supply pipe 9 in any suitable way, being herein shown as welded thereto. At its upper end, the pipe section 19 is screw-threaded as indicated at 20 and a pair of nuts 21 located on opposite sides of the ear 17 serve to secure the bracket 13 rigidly to the pipe section.

The upper section of the telescoping pipe 85 connection 8 comprises a relatively smaller pipe section 22 depending from the burner bowl 7 at one edge thereof and communicating with the interior of the bowl. This pipe section 22 depends into the lower pipe section 19 for sliding engagement therewith, a suitable stuffing box 23 being provided to seal the joint.

The burner is adapted to be raised and lowered by the manipulation of a handle 95 24 mounted on the forward end of a horizontally disposed operating rod 25 which extends in a front to rear direction through the vertical portion 11 of the front plate 10, a suitable aperture 26 being provided in the front plate to receive the rod 25. The operating handle as thus arranged is conveniently located so as to be readily accessible. At its rear end the rod 25 has a screw 27 rigid therewith and engaging a nut 28 rigid 100 with the bracket 13. Hence, in the rotation of the rod by the handle 24 an axial movement is imparted to the rod which is transmitted to the burner through means which will presently be described, to raise and 105 110

lower the same. The nut 28 is in the form of a plate or block of suitable thickness which is secured in the present instance to the bracket by means of bolts 29 entered through lugs 30 struck up from the face of the bracket in perpendicular relation thereto, these lugs being suitably apertured to receive the bolts.

The operative connection between the screw and the burner comprises in the present instance a bell crank lever 31 fulcrumed on the bracket 13 as by means of a bolt 32, a washer 33 being preferably interposed between the lever and the bracket to space the lever outwardly from the bracket. One arm 34 of the lever 31 has a pin-and-slot connection 35 with a block 36 swivelled on the rear end of the rod 25, a portion of the rod extending rearwardly from the screw 27. The other or upper arm 37 has a pin-and-slot connection 38 at its free end with the lower end of an arm 39 rigidly secured at its upper end to one edge of the burner bowl adjacent the pipe section 22. The connection 28 may consist of a bolt 40 operating in a slot 41 in the lever arm 37 and also operating in a vertical guide slot 42 in the bracket 13.

It will be seen that the axial movements imparted to the rod 25 by turning the handle 24 will swing the lever 31 to cause the burner bowl 7 to raise or lower, and that when the burner has been adjusted in any desired position, it will be effectually sustained or locked in such position by a part of the operating means itself, viz, the screw and nut, the latter it being observed, being rigid with the stove structure. Preferably the proportioning of the parts is such that the screw has a relatively snugly fitting engagement with the nut 28 so that a positive rotational movement must be imparted to the handle before the position of the burner can be altered. To thus lock the burner in its adjusted position is important, for the efficient operation of the stove requires that the burner shall not be capable of accidental

movement out of adjusted relation, the height of the burner flame being dependent upon this adjustment.

For convenience in adjusting the burner, an indicating means is preferably provided comprising an angular plate 43 having a rearwardly extending portion secured to the arm 39 and a front portion bearing the legends "High", "Med.", and "Low". Coacting with this indicator plate a finger or pointer 44 is mounted on the bracket 13 just rearwardly of the upper portion 12 of the front plate 10, said finger having a forwardly extending portion which may be secured in position upon the upper flange of the bracket by means of one of the screws which connect the front plate to the bracket.

I claim as my invention:

1. A wickless oil burner comprising, in combination, a stove body, a burner bowl, a vertical fuel supply pipe, a pipe connected to and carried by the bowl telescoping with the vertical supply pipe, a vertically movable support for the bowl, a pivoted lever having a pin and slot connection with said support and a shaft having rotatable screw-threaded engagement with a fixed portion of said stove body and having operative connection with said pivoted lever.

2. A wickless oil burner comprising, in combination, a burner bowl, means communicating with said bowl for the supply of oil thereto, a vertically movable support for said bowl, guiding means for the vertical movement of said support and bowl, a rotatable shaft having screw-threaded engagement in a stationary bearing, and a stationary pivoted bell crank, one arm thereof having an operative connection with said shaft and the other arm having operative connection with said support whereby the axial movement of said shaft effects the vertical movement of said support.

In testimony whereof, I have hereunto affixed my signature.

CHARLES M. FITCH.
